BICONICAL ELECTROMAGNETIC HORN

Wilmer L. Barrow, Manhasset, N. Y.

Application February 19, 1946, Serial No. 648,767

4 Claims. (Cl. 250—33.63)

1

The present invention relates to radio-antenna systems comprising electromagnetic horns, and more particularly biconical horns. The present application is a continuation-in-part of application, Serial No. 155,489, filed July 24, 1937, now Patent No. 2,425,716.

An object of the present invention is to provide a new and improved electromagnetic horn suitable for radiating or absorbing at ultra-high frequencies uniformly and substantially in all directions of azimuth in a plane along the surface of a cone, or along other surfaces of revolution.

Other and further objects will be explained hereinafter and will be particularly pointed out in the appended claims.

The invention will now be more fully described in connection with the accompanying drawings, in which Fig. 1 is a diagrammatic view of circuits and apparatus showing, in perspective, an electromagnetic biconical horn embodying the present invention, vertically disposed, and connected to suitable sending equipment through the medium of a coaxial line; and Fig. 2 is a similar view of a modified horn connected to a hollow-pipe-transmission line.

In Fig. 1, there is shown, for illustrative purposes, a transmission system comprising an ultra-high-frequency-oscillator electromagnetic-wave translating means 2, provided with a modulator 3, which may be modulated in any desired way, as by means of a microphone 4. The modulated output may be fed to a radio-frequency amplifier 6 that may be coupled to a circuit 8 having two-wire output-conductor connecting leads 10 and 12. One of the leads, as the lead 10, is shown connected to the lower end of the outer tubular or cylindrical conducting body portion 35 of a coaxial-line system. The tubular member 35 thus serves as a conductor to which some of the electric lines of force are attached. The other lead, as the lead 12, is shown connected to the lower end of the inner conducting exciting or absorbing stem or rod 14 of the coaxial-line system, disposed approximately axially of the tubular body portion 35. The leads 10 and 12 may, however, be connected to other types of terminal device, including conventional parallel-line or other systems and, in particular, to an elongated vertically disposed tubular-conductor hollow-pipe uniconductor wave-guide transmission system 27, shown in Fig. 2 as electrically open at its upper end and of circular cross-section. The wave-guide 27 may enclose air or any other suitable dielectric medium, and its transverse dimension is substantially equal to or

2

slightly greater than the critical dimension for the lowest-order electromagnetic waves that will pass through the hollow pipe 27.

The upper end of the outer tubular body portion 35 of the coaxial-line system of Fig. 1, and of the hollow-pipe guide 27 of Fig. 2, is shown, at 25 and 23, respectively, smoothly, roundly and continuously flaring externally back on itself, with a slight curve, to flare gradually outward into a lower conductive horn-member expande 29. The upper extremities of the slightly flaring portion of the tubular body portion 35 and of the hollow-pipe guide thus carry the lower horn member 29 to couple the horn member 29 to the upper axial end of the tubular member 35 of Fig. 1 and the electromagnetic wave-guiding passage defined by the wave-guide 27 of Fig. 2, respectively.

The conductive expande 29, moreover, becomes thus provided with an opening or aperture therein near its inner axial end, where it is joined to the upper extremity of the slightly flaring portion 23 or 25. The wave-guide 27 opens into the said passage near the said inner end thereof for the transmission of the waves through the interior thereof. The translating means 2 is removed from the said open end, as it is connected by the conductors 10 and 12 at the lower end of the coaxial line 35, 14 and the wave-guide 27, respectively.

The upper end of the inner rod 14 of the coaxial line 35, 14 is joined to an upper conductive horn-member expande 31, shown flaring continuously vertically outward from its junction with the member 14 to constitute, with the horn member 29, an outwardly directed biconical horn defining a flaring radial transmission line. In or near the central interior or throat region of the biconical horn, where the corresponding horn-like member 31 of Fig. 1 is joined to the rod 14, the upper horn member 31 of Fig. 2 is shown provided with an apex 33 which may, if desired, be pointed. The small apical end 33 of the member 31 is shown extending down into the upper portion of the hollow-pipe guide 27.

The horn members 29 and 31 are provided with juxtaposed surfaces of revolution coaxial with the wave-guide 27 and the coaxial-line system 35, 14, respectively, at the center of the biconical horn, and inverted with respect to each other, upward and downward, respectively. The common axis of the horn members 29 and 31 and of the coaxial line 35, 14, as well as of the wave-guide 27 along which the horn members 29 and 31 are spaced vertically in substantially vertical

alinement with each other, may be defined as the principal axis or line of reference of the biconical horn.

A radio-broadcast antenna system is thus provided, comprising a biconical horn defining a pair of conductive expanses 29 and 31 spaced apart in axial alinement but juxtaposed and shaped to form between them a wave-guiding transmission line mounted at the open upper end of the wave-guide 27 or at the upper end of the coaxial line 35, 14. The biconical wave-guiding transmission line guides the waves between the said open upper end and the outer peripheral extremity of the transmission line. The transmission line comprises an annular wave-guiding passage or space, in the form of a solid of revolution, of rather small or minimum thickness at the said line of reference, but expanding on all sides therefrom to flare progressively outward, in all azimuthal planes, into a large peripheral portion at the exterior or outer end region of the horn that is electrically open to free space, in order to permit the horn to receive ultra-high-frequency electromagnetic waves from space or to transmit electromagnetic waves out into space. The upper ends of the wave-guide 27 and of the coaxial line 35, 14 are correspondingly open for the radiation or reception of the waves through the biconical-horn wave-guiding annular space or passage. The biconical horn 29, 31 is thus excited centrally, at its interior or throat, by means, respectively, of the coaxial line 35, 14, and the wave-guide 27, the interior of which is disposed in communicating relation with this annular wave-guiding passage, and it similarly absorbs waves from space 35 centrally, at its interior.

The horn members 29 and 31 may be constituted of formed sheets of conducting material, like metal, such as copper or aluminum, or they may be constituted of other material if their inner or oppositely disposed walls are otherwise rendered conductors of the waves. The same applies to the tubular portion 35 of Fig. 1 and the hollow-pipe guide 27 of Fig. 2. If constituted of metal of other conducting material, the wave-guide 27 will shield the waves therein.

The surfaces of revolution of the horn members 29 and 31 may be constituted of frusto-conical flanges. They are preferably not truly conical, however, but approximately or substantially 50 so, being shown curved somewhat away from the true cone shape in order that the annular biconical-horn wave-guiding space between them may flaringly expand more rapidly than linearly. The horn members 29 and 31 are thus enabled to cooperate better for the purpose of enhancing the horizontal directivity of the biconical-horn radiation and increasing the frequency response. Whether or not strictly conical, however, the biconical horn is circularly symmetrical about its 60 principal axis.

The flaring upper ends 23 and 25 of the wave-guide 27 and the tubular portion 35 of the coaxial line 35, 14, respectively, function not only as wave-guide feeders, but also as vertically disposed horns. They are shown flaring but slightly, in order that the lengths of the horns 23 and 25 thereby provided may be at least several times the wave-length of the waves radiated or received by the biconical horn. The biconical-horn structure is shown arranged as a horizontally directed continuation of the vertically disposed portion 23 or 25. The gradual expansion of the electromagnetic field comprising the guided waves initiated by the horns 23 and 25, therefore, becomes

increased by the biconical horn. The conductive surfaces 29 and 31 will modify the radiation pattern of the wave-guide 27 or the coaxial line 35, 14, by impeding radiation of the wave launched or otherwise introduced into the wave-guide 27 for transmission to the said upper open end, or transmitted to the biconical horn by the coaxial system, 35, 14, thereby enhancing their radiation in the horizontal direction. For a given degree of electromagnetic-field expansion, therefore, a smaller biconical horn structure 29, 31 is required than would have been the case in the absence of the horn-like feeder 23 or 25.

The horn members 29 and 31 are shown lying substantially wholly on opposite sides of a horizontal plane through the center of the biconical horn, substantially at right angles to its principal axis, at the upper end of the wave-guide 27 or the coaxial line 25, 14. The directivity pattern 15 will therefore be such that the main portion of the radiant energy will be concentrated in that horizontal plane. Depending upon the shapes of the horn members 29 and 31, however, the waves 20 may be radiated out at any convenient angle to the horizontal.

Sending or receiving apparatus may be connected to the two-wire connecting leads 10 and 12.

As before stated, Fig. 1 illustrates a sending system. The corresponding connections for receiving radio waves intercepted by the said annular passage of the biconical horn at the exterior periphery thereof, from free space, will be understood by persons skilled in the art without further illustration. The coaxial line 35, 14 or the wave-guide 27, as the case may be, is connected to sending translating apparatus 2 for exciting the biconical-wave-guide transmission line, or with receiving translating apparatus (not shown) for receiving radio waves intercepted from space. The connection is shown as effected by means of the two-wire connecting leads 10 and 12, either through the coaxial line 35, 14 or through the tubular-conductor hollow-pipe wave-guide 27. The biconical horn 29, 31 is thus excited centrally, at its interior or throat, by means, respectively, of the coaxial line 35, 14, and the wave-guide 27, the interior of which is disposed in communicating relation with the annular wave-guiding passage, and it similarly absorbs waves from space centrally, at its interior. In both sending and receiving, the sending translating means 2 or the corresponding receiving translation means (not shown) is coupled through the opening or aperture at the upper end of the coaxial line 35, 14 or the wave-guide 27, in radio-wave-energy transfer relation, at the central end of the biconical-horn transmission line, to the radial transmission line provided by the biconical wave-guiding passage between the horn members 29 and 31, for transferring energy from or to the biconical horn.

In transmission, in the system of Fig. 1, modulated ultra-high-frequency electromagnetic energy may be taken by the conductors 10 and 12 from the sending translating apparatus 2 and delivered to the concentric line 35, 14, by which it will be transmitted to the said interior or throat of the horn. In the system of Fig. 2, dielectrically guided electromagnetic waves may be conducted by the conductors 10 and 12 to the lower end of the wave-guide 27, so as to be launched or transmitted upward along the wave-guide 27. The modulated electromagnetic energy will then be propagated radially outward through the said annular wave-guiding space or passage of the biconical transmission line to the said large exterior

peripheral portion of the biconical horn. Upon arrival at this peripheral portion of the biconical horn, the electromagnetic waves become readily disattached from the horn, continuing thereafter to travel beyond this peripheral portion, for radiation forward out into free space, as ordinary modulated radio waves. The waves will be radiated outward into space substantially uniformly in all directions of azimuth along the periphery of this transmission line. The biconical horn 29, 31 thus constitutes a directive electromagnetic radiator.

Similar but reverse operation will take place during reception of such waves. The modulated electromagnetic waves will be received at the large periphery of the biconical horn 29, 31 and, after traveling through the flared biconical-horn annular space, will be absorbed by the coaxial line 14, 35 or the wave-guide 27, and will be communicated to the conductors 10 and 12, by which they will be conducted to a receiving system (not shown), where the signals comprising the intelligence will be demodulated.

The biconical horn may thus be connected to sending or receiving apparatus, at its throat interior, and to free space, at its periphery, for purposes of either radiating radio waves into, or absorbing them from, space. If the biconical horn is used for the transmission or the reception of ultra-high-frequency waves of wave-lengths below ten meters, its dimensions may be kept reasonably small.

The horn members 29 and 31 of the biconical horn are provided with flaring guiding surfaces or guiding walls, of progressively greater cross-sectional area from the interior of the biconical horn toward its periphery, that connect the interior of the horn with its periphery. The biconical horn thus operates to guide the electromagnetic waves traveling through the dielectric within it tangentially along the said conducting guiding surfaces in all directions of azimuth smoothly, continuously, and without interruption. In reception, the electromagnetic waves received from space at the periphery of the biconical horn are thus guided by the said surfaces to its throat interior. In transmission, the electromagnetic waves generated at the interior of the horn are guided along the said surfaces to the periphery thereof, for propagation forward out into space. The waves become thus slidingly attached to the guiding surfaces and they remain so continuously attached throughout their sliding guided movement along this horn surface, from the throat interior of the biconical horn until they reach the exterior periphery thereof. A similar operation takes place during reception.

The higher-order waves travel through the dielectric of the wave-guiding biconical-horn passage with a phase velocity different from that of light. Near the throat of the horn, the phase velocity may be very much greater than the velocity of light. The phase velocity decreases as the periphery of the biconical horn is reached, until just at or beyond the periphery, the phase velocity may be exactly the same as that of light.

The distance between the base edges 39 and 41 of the horn members 29 and 31 may be several wave-lengths. The radial length of the biconical transmission line, or the distance between the junction of the horn member 31 to the rod 14 of Fig. 1, or between the apex 33 of the horn member 31 of Fig. 2, at the axial end at the throat of the horn, to its exterior peripheral end, may be varied over wide limits, from a preferably small value,

at least a wave-length, up to substantially greater than a wave-length or more, of the waves guided by the biconical-horn transmission system. Particular distances, however, are peculiarly adapted to the excitation of waves of particular types in the horn; for different types of horn waves, and combinations of the same, may be separately excited and propagated within the horn for transmission, or absorbed by the horn, for reception. Higher-order types of waves are discussed by S. A. Schelkunoff in two articles, entitled, "Transmission Theory of Spherical Waves," Bell System Monograph B-1092, 1939, and "Transmission Theory of Plane Electromagnetic Waves," Proceedings of the Institute of Radio Engineers, vol. 25, pp. 1457-1492, November, 1937.

Lower-order symmetric vertically polarized transverse electromagnetic or TEM horn waves may be excited or received at or near the center of throat of the biconical horn. The magnetic and electrostatic lines of the TEM wave are both transverse to the direction of propagation. The TEM is the simplest type of wave wherein the magnetic lines form concentric circles about the principal axis of the biconical horn 29, 31, and wherein the electrostatic lines extend in arcs between the horn members 29 and 31.

Other waves sometimes used in biconical horns are of transverse magnetic or TM type. These waves have their electric lines in the form of partial loops extending radially from the walls of the guides toward the center, then longitudinally along the horn and then back to the wall from which they started, and may have additional closed loops in the space between the two surfaces in higher orders. The magnetic lines are circles concentric with the axis of the tube and linking through the partial loops of the electric lines so that these magnetic lines are wholly transverse to the direction of propagation. Examples are $TM_{0,1}$ and $TM_{0,2}$ waves.

The electrostatic lines of the lower-order horizontally polarized transverse electric or $TE_{0,1}$ wave, like those of the TEM wave, are wholly transverse to the direction of propagation. They form concentric circles about the principal axis of the biconical horn 29, 31. The corresponding magnetic lines, however, are partly transverse and partly longitudinal. They form loops linking about the electrostatic lines, and lying wholly in radial planes passing through the principal axis of the biconical horn.

The invention is not limited to the exact embodiments thereof that are illustrated and described herein. Further modifications may be made by persons skilled in the art without departing from the spirit and scope of the invention, as described in the appended claims.

What is claimed is:

1. An electromagnetic horn comprising a pair of metallic continuously curved wave guide members spaced apart in axial alignment with each other to form an outwardly flaring radial transmission line, the radial length of said line being substantially greater than a wave-length at the operating radio frequency and the angle of flare being acute, and electromagnetic wave translating means at the central end of said line for exciting said line or for receiving radio wave power intercepted thereby.

2. A radio-antenna system comprising a pair of continuously curved conductive expanses juxtaposed and shaped to form between them a

wave-guiding passage that flares outward from an inner region to an outer region that is open to free space for the radiation or reception of radio waves, the passage having a length greater than one wavelength and sufficient to take on wave guide properties, and wave guide exciting or receiving means coupled to the passage at the inner region.

3. A radio-antenna system comprising a pair of curved conductive expanses juxtaposed and shaped to form between them a wave-guiding passage that flares outward from an inner region to an outer region that is open to free space for the radiation or reception of radio waves, the passage having a length greater than the wave-length of the waves, one of the conductive expanses having an opening at the inner region of the passage, and wave guide means coupled through the opening in wave-energy-transfer-relation with the passage.

4. A directive radiating system comprising two extended wave guiding members at least one wavelength long disposed adjacent each other and shaped so that at least their proximate surfaces have substantially the form of curved surfaces of revolution about a common axis, at least one of said surfaces being sufficiently convex so

that the included space between said surfaces has substantially the form of a solid of revolution whose thickness is least near said axis, wave guide translating means, and coupling means coupling said wave translating means to the space between said surfaces adjacent said axis whereby coupling of said wave translating means to the surrounding free space is effected directly.
